UNITED STATES PATENT OFFICE.

WILLIAM H. JOHNSON, OF DELHI, NEW YORK, ASSIGNOR OF ONE-HALF TO
MARCUS O. LANDON, OF SAME PLACE.

NECK-YOKE RING.

SPECIFICATION forming part of Letters Patent No. 406,914, dated July 16, 1889.

Application filed April 20, 1889. Serial No. 308,032. (No model.)

To all whom it may concern:

Be it known that I, WILLIAM H. JOHNSON, a citizen of the United States, residing at Delhi, in the county of Delaware and State of New York, have invented certain new and useful Improvements in Neck - Yoke Rings and Breast-Strap Drum Rollers; and I do hereby declare the following to be a full, clear, and exact description of the invention, such as will enable others skilled in the art to which it appertains to make and use the same.

My invention consists, mainly, in an improved new article of manufacture—viz., a hollow roller for a breast-strap and neck-yoke ring, said roller having a passage through it for the neck-yoke ring, which passage is flared at each end concentrically with said ring, and between said flared bearing ends is made parallel or is chambered all around, so as to isolate the ring from the interior surface of the barrel of the roller except at those points where, by reason of corresponding concentricity of the roller and ring, a contact is allowed, thus affording room for the curve of the ring between the points of contact, reducing friction, and adapting the roller for rings of different thicknesses and diameters.

My invention also consists in the said roller made with the peculiar passage described and having flanges at right angles to its longitudinal axis and quite broad, so as to positively retain the breast-strap in a flatwise position upon the barrel of the roller. The said roller, made with the peculiar passage and flanges described, may be cast in one piece or cast in halves with lugs and perforations and said halves united and secured upon the ring by screws or other fastenings.

In the accompanying drawings, Figure 1 is a vertical central section of my improved drum roller applied on a neck-yoke ring and with breast-strap attached to it, and Fig. 2 is an end view of the same. Fig. 3 is a perspective view illustrating my invention as in use.

A in the drawings represents an ordinary neck-yoke, B an ordinary breast-strap, and C an ordinary breast-strap and neck-yoke ring.

D is my improved drum roller, cast, preferably, in two parts, as shown; but it may be cast in one piece and the ring, after being

passed through the roller and the eye of the neck-yoke, welded. As shown, the roller is cast in equal halves, and the respective halves are formed with a semi-cylindrical body portion *a*, having a wide flange *b* at right angles to the longitudinal axis of the roller D. The outer surface of each of the halves is straight and uniform from flange to flange, while the interior surface, which forms one-half of the passage for the ring C, is irregular, being flared at each end for a portion of the length of the roller, as shown at *c c*, and shouldered at *d*, so as to form a chamber *d'* all around between said flared ends *c c*, as shown. The flared portions *c c* are concentric with the ring C, while the chambered portion *d'* may be parallel with the outer periphery of the roller. By this construction the ring has a bearing only upon the concentric flared portions of the roller, and thus undue friction is avoided; and by having spaced bearing-surfaces the one roller may be used to a limited extent for rings of different thicknesses and diameter. On one of the halves forming the roller-drum integral perforated lugs *f* are provided on each of the flanges, and in the flanges of the other half holes are formed, and when the ring C and the halves are placed together, as shown, screws or other fastenings *g* are passed through the lugs and flanges, and the whole thereby securely united.

At *xx'* in Fig. 1 I have illustrated by dotted lines that the chamber might be made longer by making each of the bearings *c c* shorter, this being done by cutting away those portions of the bearings *c c* extending from *x* to *x'* on each side of the vertical transverse axis of the roller and forming the chamber or parallel inner surface between the points *xx*, instead of between *x' x'*.

What I claim is—

1. The within-described improved article of manufacture, consisting of a flanged roller for the neck-yoke ring and breast-strap of harness, said roller being formed with a passage through it which is flared concentrically with the ring at each end, and provided with an interior annular groove between said flared ends, substantially as described.

2. The within-described improved article of manufacture, consisting of the flanged roller

for the neck-yoke ring and breast-strap of harness, said roller being formed of halves, the flanges of one half being provided with perforated lugs and of the other half with 5 perforations, and the passage for the ring being flared concentrically with the ring at each end and provided with an interior annular groove between said concentric portions, and

the whole united upon the ring by suitable fastenings, substantially as described.

In testimony whereof I affix my signature in presence of two witnesses.

WILLIAM H. JOHNSON.
